UNITED STATES PATENT OFFICE.

ALBERT H. TINNERMAN, OF CLEVELAND, OHIO.

STOVE-OVEN FRONT FRAME.

Application filed July 31, 1923. Serial No. 654,936.

To all whom it may concern:

Be it known that I, ALBERT H. TINNERMAN, a citizen of the United States, residing at Cleveland, in the county of Cuyahoga and State of Ohio, have invented a certain new and useful Improvement in a Stove-Oven Front Frame, of which the following is a full, clear, and exact description, reference being had to the accompanying drawings.

This invention relates to stoves and has for its general object the provision of a novel stove construction directed to the maintenance of a uniform appearance of the exposed parts of the stove.

It is now the trade custom to provide stoves, such as kitchen ranges, with all of the exposed, exterior surfaces plated, or enamelled to enhance the appearance of the stove as well as to afford ease in cleaning. The usual surfacing is in the form of a vitreous enamel which is applied to and baked on the various panels and parts, comprising the stove, before the stove is assembled. This practice has introduced many difficulties in the economical manufacture of those exposed enameled parts which are subjected to intense heat. This is particularly true of the enameled panel portions and frame members which comprise the front wall of the oven and door frame. For instance, where there is a baking oven superposed over a broiler, that portion of the front frame of the stove intermediate the oven and broiler doors frequently becomes discolored by heat concentrating in the broiler adjacent thereto. This heat escapes upwardly when the broiler door is opened and eventually the enamel on that portion of the frame tends to discolor and to crack. This necessitates the replacement of the entire front frame if a neat appearance is to be maintained. Considerable expense is thus incurred in dismounting the damaged stove frame to substitute a new frame.

A more specific object of my invention therefore, is the provision of a front frame construction for stoves of the class referred to, which will eliminate the foregoing stated objections to present day stove constructions. To this end I provide readily replaceable panels or members comprising those portions of the enameled frame which are subjected to the damaging influence of heat from the broiler or oven.

Other objects of my invention will herein-

after be set forth in the following description which refers to the accompanying drawings which embody a preferred form thereof. The essential characteristics are summarized in the claims.

In the drawings, Fig. 1 is a fragmentary elevation of a front frame for a stove embodying my novel replaceable panel construction; Fig. 2 is a cross sectional side elevation taken through the broiler and oven of a stove with my novel frame arrangement incorporated in the construction thereof; Fig. 3 is an enlarged cross sectional view corresponding to line 3—3 of Fig. 1 and which is taken through that portion of the door frame which is subjected to the greatest heat, namely that portion disposed intermediate the oven and broiler doors.

In fulfilling the objects of my invention I provide a frame which may be enameled on all of its exposed surfaces and which may be readily attached to the top, side and oven panels of the stove. This frame also comprises a supporting means for swingable oven doors which may be readily removed when it is desired to clean the stove. That portion of the stove comprising the front wall intermediate the top and bottom oven may, in one form of my invention, be formed integrally with the front frame in which case a replaceable panel member is provided to furnish the finished or enameled effect. This portion of the frame may comprise a separate readily replaceable member which may be removed without necessitating the removal of the front frame of the stove.

As shown in Figs. 1 and 2 a front stove frame, embodying one form of my invention, may have the usual rectangular shape with top and bottom portions 7 and 8 provided with depressed, door engaging flanges 9. The flanges 9 may extend completely around the inner edges of the frame. An intermediate frame portion 10, constituting that portion of the front frame between the top oven 11, see Fig. 2, and the bottom oven or broiler 12 may have the outer face thereof formed in the same plane as the door contacting faces of the depressed flanges 9.

The vertical portions 14 of the frame are provided with depressed surfaces for the attachment of oven door hinges and broiler door hinges 15 and 16 respectively. These hinges may be enameled or polished as desired.

To complete the symmetrical appearance

of the front of the range as well as to obtain the replaceable panel feature referred to, I provide an enameled panel member 18 which, in outer appearance conforms to the appearance 5 of the top and bottom frame portions 7 and 8 and the side portions 14. This panel member is attached to the intermediate frame portion 10 in the manner shown in Fig. 3. It will be noted that the frame portion 10 is provided with openings 20 in which internally threaded lugs 21, formed on the rear face of the removable panel 18, may extend. The panel member may be maintained with the lugs thereof in the 10 opening 20 by any suitable means such as ordinary screw members 22 and washers 23. An annular flange 24 is provided to surround the opening 20, whereby a proper clamping seat is provided for washers 23.

15 20 The application of this frame structure to a stove construction such as is illustrated in Fig. 2, wherein the baking oven is located above the broiler so that one set of burners 27 supplies the heat for both the broiler and the baking oven, is particularly advantageous 25 in that if the enamel finish of the panel 18 is discolored due to heat accumulating in the broiler adjacent the panel, the damaged panel may be readily removed and 30 a new panel expeditiously substituted therefor. This may be accomplished of course, without necessitating the dismounting of the entire front of the stove as has heretofore been the practice.

35 40 If desired, the front stove frame described, may be formed of pressed metal or may comprise a casting. I prefer however, to form the frame of gray iron, as gray iron castings of this character may be more readily baked during the enameling process. In this case, I provide strengthening ribs 25 and 26 on the back of the intermediate portion 10 which serve the purpose of preventing warping 45 of the castings during the enamel baking as well as affording ledges or shoulders upon which the inner oven panel members may be secured. Similar ribs or lugs 27 may be formed on the back of the top portion 7 and side portions 14.

50 55 60 65 As shown in Fig. 2, the top outer panel 30 has the front edge thereof bent downwardly and flanged as shown at 31 to engage the rib 27. The outer side panels may be similarly formed to engage the side lugs 27 of the frame member. Similarly, the partitioning panel 32 which divides the interior of the stove into the oven 11 and broiler 12 may engage the rib 25 formed on the intermediate casting portion 10. In the broiler compartment immediately adjacent the frame portion 10, the tendency of this portion of the stove frame is to warp and discolor due to its proximity to the burners and the back of the panel member 18 is formed to provide an air space between the

portion 10 and panel 18 to prevent the conduction of heat to the outer enameled surface 18^a of the panel member 18. As shown in Fig. 3, the back face of the panel member 18 is depressed, there being only spaced 70 apart marginal contacting portions 40 along the top and bottom edges of the panel 18.

Furthermore, it will be readily understood that by the use of either of the foregoing described constructions, it is commercially practical for the stove manufacturer or dealer to give a warranty with the sale of his product as to the lasting qualities of an all enameled stove with the assurance that replacement service would involve only 80 a minimum expenditure commensurate with a sales advantage which a permanency in finish and attractiveness in appearance affords particularly where an all white enameled stove is being manufactured. 85

I claim:

1. In a stove of the character described having a broiler oven and a top oven disposed thereabove, the combination of an integral frame comprising the front wall of 90 the oven and broiler, a door for the top oven swingably mounted on the frame, a similarly mounted door for the broiler, said frame having an intermediate portion dividing the frame to define the door openings 95 for the oven and broiler and a replaceable panel member mounted on said dividing portion of the frame, the panel member conforming in appearance with the exposed portions of the frame. 100

2. In a cooking range of the character described, an enameled front oven frame member constituting the front wall of a baking oven and a broiler oven disposed therebeneath, said frame member having an intermediate portion dividing the frame into oven and broiler door openings, and a panel mounted on said portion in such manner as to be readily replaceable without dismounting the frame from the stove. 105

3. In a cooking range, a front frame having a broiler oven and baking oven doorway, doors mounted on the frame for closing said doorways and a removable member attached to the frame intermediate said doors and independently of the door mountings. 110

4. In a cooking range of the character described, the combination of a rectangular stove frame having an upper and a lower door opening formed therein, hinge members attached to side portions of the frame adjacent the lower corners of the door openings, swingable doors mounted thereon, said frame having flanges constituting a seat for the doors when closed, an intermediate frame portion extending between the door openings, said flanges merging into said intermediate portion, and a removable panel member positioned upon said intermediate portion of the frame, said removable panel 120 125 130

having the ends thereof in matched relation to the side portions of the frame whereby the finished appearance of the frame may be maintained.

- 5 5. In a cooking range, a rectangular front stove frame member having a broiler and an oven door opening and a replaceable panel member disposed between the doors to overlie a part of the frame.
- 10 6. In a cooking range of the character de-

scribed having oven doors, a front structure comprising a door frame of a broiler and oven, said frame having a removable replaceable member mounted independently of the doors and disposed adjacent the top part 15 of one of the stove compartments comprising the oven or broiler.

In testimony whereof, I hereunto affix my signature.

ALBERT H. TINNERMAN.
